Primary Examiner — Ricky Pham*(74) Attorney, Agent, or Firm* — Mark R. Malek; Zies Widerman & Malek**CLAIM**

The ornamental design for a multi-pocket cooking pan, as shown and described.

DESCRIPTION

FIG. 1 is a top perspective view of a multi-pocket cooking pan of the present invention.

FIG. 2 is a bottom perspective view of the multi-pocket cooking pan illustrated in FIG. 1.

FIG. 3 is a top plan view of the multi-pocket cooking pan illustrated in FIG. 1.

FIG. 4 is a side elevation view of the multi-pocket cooking pan illustrated in FIG. 1; and,

FIG. 5 is a bottom plan view of the multi-pocket cooking pan illustrated in FIG. 1.

The broken lines depict a cutting tool to be used in connection with the multi-pocket cooking pan, and do not form a claimed feature of the present invention.
